Chappell & Earl.
Attorneys.

UNITED STATES PATENT OFFICE.

HUBERT R. HUMPHREY, OF KALAMAZOO, MICHIGAN, ASSIGNOR TO GENERAL GAS LIGHT COMPANY, OF KALAMAZOO, MICHIGAN.

GAS HEATER.

Application filed October 23, 1922. Serial No. 596,414.

To all whom it may concern:

Be it known that I, HUBERT R. HUMPHREY, a citizen of the United States, residing at the city and county of Kalamazoo, 5 State of Michigan, have invented certain new and useful improvements in Gas Heaters, of which the following is a specification.

This invention relates to improvements in gas heaters, which are adapted to be installed in fireplaces.

The main object of the invention is to provide such a gas heater in which the burner and valves are concealed from view and at the same time readily accessible for adjustment or manipulation should occasion require.

Further objects, and objects relating to structural details, will definitely appear from the detailed description to follow:

20 I accomplish the objects of my invention by the devices and means described in the following specification. The invention is clearly defined and pointed out in the claims.

A structure which is a preferred embodiment of my invention is clearly illustrated in the accompanying drawings, forming a part of this application, in which:

Fig. I is a front perspective view of a gas heater embodying the features of my invention.

Fig. II is an end view with parts broken away for convenience in illustration.

Fig. III is a vertical central section on a line corresponding to line 3—3 of Fig. I, 35 certain parts being shown in full lines for convenience in illustration.

Fig. IV is a detail front elevation with the front frame removed, a portion of the burner and fireback being broken away.

40 Fig. V is a fragmentary front perspective view of a modified form of my invention, the modification being in the form of the front frame.

Fig. VI is an end elevation of the embodiment shown in Fig. V, parts being broken away for convenience in illustration.

Fig. VII is a front perspective view of another modification or embodiment of my invention, the parts being broken away to show structural details, the modification being mainly in the valve operating mechanism.

Fig. VIII is a detail view mainly in vertical section on a line corresponding to line 55 8—8 of Fig. VII.

In the drawings similar reference numerals refer to similar parts throughout the several views and the sectional views are taken looking in the direction of the little arrows at the ends of the section lines.

Referring to the drawings the body of my improved heater comprises a back wall 1 and side walls 2, the back and side walls being preferably a sheet metal stamping. The rear legs 3 are secured to this back wall. 60 I also provide a front frame comprising side members 4 and a front horizontal member 5 extending between the side members. This frame is of suitable shape and ornamentation, the lower portion being, pref. 70 erably forwardly offset as shown. The front legs 6 are integral with the side members 4. The side walls have flanges 7 to which the side members of the front frame are secured.

Within the walls 1 mount a supporting plate 8, the fireback 9 being arranged on this supporting plate, the radiating elements 10 being also arranged on this supporting plate in front of the fireback. The burner, 80 designated generally by the numeral 11, is mounted below the supporting plate within the walls and front frame which constitutes a housing therefor. The burner is provided with a valve 12 which is also within this housing, the stem 13 of the valve projecting forwardly and being provided with a hand wheel 14.

The space between the supporting plate, the front 5 and the end members provides 90 an opening through which the parts of the burner and valve are accessible for manipulation and adjustment. This manipulation and adjustment can be effected after the heater is positioned in a fireplace opening. 95 This opening is normally closed by the hearthplate 15 which rests in the shouldered ledges 16 in the supporting plate, front piece and end members. This hearth plate is readily removed to expose the housed parts of 100 the burner and valve.

In the modification shown in Figs. V and VI the parts are substantially the same with the exception that the front frame members 17 and 18 are of another type.

105 In the modification shown in Figs. VII and VIII an electromagnet 19 is arranged within the housing to actuate the valve ratchet mechanism 20, thus providing means for electrically actuating the valve 110

21. However, as the details of this form no part of my present invention I do not describe the same with further detail herein. I have shown these modifications for the purpose of showing the adaptability of my improvements.

Having thus described my invention, what I claim as new and desire to secure by Letters Patent, is:

- 10 1. In a gas heater, the combination with rear and side walls, of a front frame secured thereto comprising side members and a horizontal front member extending between the side members, said side members being forwardly offset at their lower ends, a supporting plate mounted within said walls, a fireback and radiating elements arranged within said walls above said supporting plate, a burner arranged and housed within said walls and frame below said supporting plate, there being an opening between said supporting plate and said front frame side and front members affording access to the burner, and a removable hearth plate 15 constituting a closure for said opening, said frame, side and front members and said supporting plate being provided with shouldered ledges receiving the edges of said hearth plate.
- 20 2. In a gas heater, the combination with rear and side walls, of a front frame secured thereto comprising side members and a horizontal front member extending between the side members, said side members being forwardly offset at their lower ends, a supporting plate mounted within said walls, a burner arranged and housed within said walls and frame below said supporting

plate, there being an opening between said supporting plate and said front frame side 40 and front members affording access to the burner, and a removable hearth plate constituting a closure for said opening, said frame, side and front members and said supporting plate being provided with shouldered ledges receiving the edges of said hearth plate. 45

3. In a gas heater, the combination with rear and side walls, of a front frame secured thereto comprising side members and a horizontal front member extending between the side members, a fireback and radiating elements arranged within said walls above said supporting plate, a burner arranged and housed within said walls and frame below 50 said supporting plate, there being an opening between said supporting plate and said front frame side and front members affording access to the burner, and a removable hearth plate constituting a closure for said 55 opening.

4. In a gas heater, the combination with rear and side walls, of a front frame secured thereto comprising side members and a horizontal frame member extending between 60 the side members, a burner arranged and housed within said walls and frame below said supporting plate, there being an opening between said supporting plate and said front frame side and front members affording access to the burner, and a removable hearth plate constituting a closure for said 65 opening.

In witness whereof, I have hereunto set my hand and seal.

HUBERT R. HUMPHREY. [L.S.]
